HANGAR

Filed July 1, 1930

UNITED STATES PATENT OFFICE

CHARLES J. CARLOTTI, OF NEW YORK, N. Y.

HANGAR

Application filed July 1, 1930. Serial No. 465,227.

This invention relates to hangars and more particularly to hangars for reception of lighter-than-air crafts.

Among the principal objects which the present invention has in view are: To provide a hangar having means for lowering and raising an aircraft through an opening in the top thereof; to provide a hangar having a rotatable roof with means for securely holding an aircraft thereto; to provide anchoring means which are movable therewith; to provide anchoring means on said roof so constructed and arranged that the craft can be brought into position above the roof head-on to the wind; to provide a roof having an opening therein which can be positioned in the direction in which the wind may be blowing; to provide means for lowering the craft into the hangar through the roof; to provide means within the hangar for receiving air-craft, and to move same to various positions within the hangar; to secure simplicity of construction and operation; and to obtain other advantages and results as may be brought out in the following description.

In the drawings:

Figure 1 is a plan view of a hangar provided with a rotatable roof and an opening therein;

Figure 2 is a sectional view as taken on the line 2—2 of Figure 1, and

Figure 3 is an enlarged fragmentary detail sectional view showing means of rotating roof of hangar.

In the description:

It is well known that the hazard of present day mooring and launching of aircrafts, particularly the dirigible type, is adverse winds. Considerable time is lost in waiting for winds to die down in order to successfully moor a dirigible to a mooring mast or bring it down to the ground preparatory to placing it in a hangar. Also, to accomplish bringing the dirigible to the ground requires vast man power, and then the dangers are not eliminated, for should a sudden gust of wind blow up, the efforts of the ground crew are made considerably more hazardous and may cause possible damage to the dirigible. These

same difficulties are encountered when moving a dirigible out from the hangar.

To overcome the above conditions, I have shown in my disclosure a hangar 10, preferably constructed of a cylindrical shape. Said hangar is provided at the top with a rotatable roof 11 of similar shape and flat surface, and provided with an elongated and preferably oval opening 12 for lowering or releasing aircrafts therethrough, and particularly aircrafts of the dirigible type. Said roof is made rotatable with respect to the side walls and may be rotated by any suitable means so as to position it to receive a dirigible coming in a direction with a favorable wind. However, in use, it is not absolutely essential to first rotate the roof so that the opening shall be in alignment with the craft, as I have provided a stationary mooring mast 13 adjacent one end of the opening, said mast being provided at the upper end with a pivoted member 14 to which the nose of a craft 15 (indicated in dotted lines) is first moored. After the craft has been thus moored, the roof may then be brought around for the opening 12 to be in position underlying the craft and longitudinal thereof.

When the roof with the opening is in the position required, a second mast 16 preferably of a mobile type oppositely positioned on the roof at the tail end of the opening is brought up in place or moved backward depending on the length of the craft to be moored. The tail of the craft is then securely attached to this tail mast as clearly shown in Figures 1 and 2. When the craft has been securely moored to both masts, the attachment of the craft is transferred from the pivoted member 14 to a means within upright slides 17 secured to both masts. Said means may be cables 18 (indicated in dotted lines in Figure 2), which are attached at their lower ends to a pair of motor-driven drums 19. Said drums are operated simultaneously when the craft is being lowered down and slides 17 so that the craft is in an even position all the way down.

When the craft has been brought down to resting position on the floor of the hangar, the lowering means may be removed from

both ends of the craft. Should it be desirable to move the craft out of the way, the nose and tail may then be made secure to a holding means 20 within a horizontal track 21 here shown as extending peripherally of the wall and carried by framework outward from the interior wall of the hangar 10 as shown in Figure 2.

To further secure the craft in the hangar, I have provided docking rails 22 in the floor of the hangar. The opening 12 in the roof 11 is rotated while the craft is being lowered so as to be in alignment with the said docking rails, and when the craft has been entirely lowered, it is then fastened to the rails, after which the craft may be secured to the holding means 20 in the wall track 21.

In order to launch a craft, it is first released from the docking rails, after which the craft is brought around to be in alignment with the slides 17 and then released from the wall track and made secure to the holding means 18 within the slides. The roof is then rotated with the craft to be in alignment with the prevailing wind and the craft is then permitted to rise under its own buoyancy to the top of the masts 13 and 16. When the craft has reached the top of the slides, the holding means in the slide of the mobile mast 18 is first detached, thereby permitting the craft to right itself and clear the said mast, after which the holding means in mast 13 is detached, and the craft under its own power sails away.

On the top of the hangar 10 and extending entirely around the periphery thereof, I have shown a pair of railway tracks 23, though other means may be employed for supporting and guiding a plurality of wheels 24 mounted on the underside of the roof 11. Said wheels are preferably of the car type having inwardly facing flanges 25 to fit and extend below the surface of the tracks. Any suitable means may be used to rotate the roof, such as automotive power and so forth.

The mobile mast 16 as illustrated is preferably mounted on a track 26 having a plurality of wheels 27 riding on a pair of tracks 28 securely fastened to the roof 11. Said tracks extend in a direction longitudinally of the opening 12 and at their forward ends extend slightly beyond said opening. Adjacent the outside periphery of the roof the tracks 28 are turned upward so as to prevent the track 26 carrying the mast 16 from becoming disengaged therefrom when moved backward, as when a ship substantially the length of the opening is to be lowered into the hangar 10.

In inclement weather, a cover of any desired size or weight may be employed to close the opening 12. Said cover may be permanently attached to the roof or placed there during bad weather if desired.

From the above disclosure it is to be noted

that large crews for handling a dirigible for mooring and launching is eliminated, and the hazards have been greatly minimized. While I have not shown any means for entering the hangar or to reach the top of the roof, doors may be conveniently placed in the hangar and ladders either inside or outside the hangar may be employed to reach the roof. As to machinery and working parts for rotating the roof, these can be placed within the hangar as all operations may be from within.

Claims:

1. A hangar for aircraft comprising a peripheral enclosure and a rotatable roof for said enclosure, said roof having an opening therein adapted to receive an aircraft therethrough. 80

2. A hangar for aircraft comprising a peripheral enclosure and a roof for said enclosure, said roof having an opening therein adapted to receive the aircraft therethrough, said roof being rotatable to place said opening longitudinally of the wind direction. 85

3. A hangar for aircraft comprising a peripheral enclosure and a rotatable roof for said enclosure, said roof having an opening therein adapted to receive the aircraft therethrough and an anchoring mast adjacent one end of said opening. 90

4. A hangar for aircraft comprising a peripheral enclosure and a roof for said enclosure, said roof having an opening therein adapted to receive the aircraft therethrough, said roof being rotatable to place the opening longitudinally of the wind direction, and an anchoring mast adjacent one end of said opening. 95 100

5. A hangar for aircraft comprising a peripheral enclosure and a rotatable roof for said enclosure, said roof having an opening therein adapted to receive the aircraft therethrough, and anchoring masts adjacent the opposite ends of said opening. 105

6. A hangar for aircraft comprising a peripheral enclosure and a roof for said enclosure, said roof having an opening therein adapted to receive the aircraft therethrough, said roof being rotatable to place the opening longitudinally of the wind direction, and anchoring masts adjacent opposite ends of said opening. 110 115

7. A hangar for aircraft comprising a peripheral enclosure and a roof for said enclosure, said roof having an opening therein adapted to receive the aircraft therethrough, and anchoring masts adjacent the opposite ends of the opening, one of said masts being movable with reference to said opening. 120

8. A hangar for aircraft comprising a peripheral enclosure and a roof for said enclosure, said roof having an opening therein adapted to receive the aircraft therethrough, said roof being rotatable to place the opening longitudinally of the wind direction, and anchoring masts adjacent the opposite ends 125 130

of said opening, one of said masts being movable with reference to said opening.

9. A hangar for aircraft comprising a peripheral enclosure and a roof for said enclosure, said roof having an opening therein adapted to receive the aircraft therethrough, anchoring masts at opposite ends of said opening, and means on said masts for lowering the aircraft through said opening.
10. A hangar for aircraft comprising a peripheral enclosure and a roof for said enclosure, said roof having an opening therein adapted to receive the aircraft therethrough, said roof being rotatable to place the opening longitudinally of the wind direction, anchoring masts at opposite ends of said opening, and means on said masts for lowering aircraft through said opening.

11. A hangar for aircraft comprising a peripheral enclosure and a roof for said enclosure, said roof having an opening therein adapted to receive the aircraft therethrough, anchoring masts at opposite ends of said opening, means on said masts for lowering aircraft through said opening, and a mooring means within the enclosure for receiving the craft when lowered.

12. A hangar for aircraft comprising a peripheral enclosure and a roof for said enclosure, said roof having an opening therein adapted to receive the aircraft therethrough, said roof having means for rotating the same to place the opening longitudinally of the wind direction, anchoring masts at opposite ends of said opening, means for lowering the aircraft moored on said masts through said opening, and a mooring rail within the enclosure for receiving the craft when so lowered.
